UNITED STATES PATENT OFFICE.

FRANK CRIEST, OF SHARPSVILLE, PENNSYLVANIA.

WALKING DOLL.

1,269,056.

Specification of Letters Patent. Patented June 11, 1918.

Application filed February 28, 1918. Serial No. 219,661.

To all whom it may concern:

Be it known that I, FRANK CRIEST, a citizen of the United States, residing at Sharpsville, in the county of Mercer and

5 State of Pennsylvania, have invented a new and Improved Walking Doll, of which the following is a specification.

My invention has reference to that class of toys in which is included a figure, which 10 may be the representation of a doll, of a bird or of an animal, and which has leg portions adapted, when the toy is pulled or pushed along the floor or other base to assume the walking attitude and my said invention primarily seeks to provide a toy of 15 the character stated, in which the several parts are so designed and provided with coöperating connections of such character that they can be economically made and 20 easily assembled, the connections being of such stable character that they are not likely to readily get out of order under the rough handling usually incident in the use of toys of this character, by children.

25 Again, my invention seeks to provide a simple and inexpensive device of the walking doll type, in which the parts are so combined that no special manipulation thereof, other than simply pulling or pushing the 30 toy along, is necessary to effect the desired walking operation and in which the connections that coöperatively join the several parts are such that in case of becoming loosened or partly separated, they can be 35 quickly and easily repaired or replaced by the child using the toy.

Again, my invention has for its object to 40 provide a simple and inexpensive toy figure of the walking type, in which the use of clock gearing spring actuated mechanism, elastic bands and the like are dispensed with, thereby reducing the cost of manufacture of 45 such toys and the danger of the toy getting out of order, to the minimum.

50 With the above and other objects in view, my invention resides in the peculiar features of construction and novel combination of the parts hereinafter described, specifically pointed out in the appended claims and generally outlined in the accompanying drawings, in which:

Figure 1 is a front perspective view of

a doll in which is embodied my invention, the same being shown in the act of walking, when pulled along in the direction of the 55 arrow *x*.

Fig. 2 is a rear perspective view of a manikin or skeleton or doll like representation, the same being shown in the act of walking, when pushed along in the direction 60 of the arrow *y*.

Fig. 3 is a horizontal section of the doll taken substantially on the line 3—3 on Fig. 1, the shiftable movements of the leg members and the double ended rocker member 65 hereinafter referred to, being indicated in dot and dash lines.

Fig. 4 is a detail perspective view of a portion of the doll body, the right leg and the rocker member, and illustrates one way 70 of forming the back stops for the leg.

Fig. 5 is a detail perspective view of the double ended rocker member.

Fig. 6 is a longitudinal section of the hand hold that is flexibly joined with the 75 pulling or pushing pole or member.

Fig. 7 is a horizontal section taken on the line 7—7 on Fig. 6.

Fig. 8 is a cross section thereof on the 80 line 8—8 on Fig. 6.

In the drawings, I have illustrated a preferred embodiment of my invention, the same being shown in imitation of a doll, either of manikin shape as shown in Fig. 2, or the customary doll shape as in Fig. 1, it 85 being understood that my invention is not to be restricted to the precise details or construction of parts shown, since they may be readily modified to represent birds, animals or other animated figures without departing 90 from the scope of the appended claims.

My toy appliance in its complete make-up embodies a body portion 1, the upper part of which may and preferably does terminate in a representation of a head 2 and shoulders 3 to which the arms 4 may be pivoted in any suitable manner.

When of manikin shape, the arms are attached by ordinary wood screws 40—40.

Coöperating with the body are two 100 straight stiff legs 5—5 and they are pivotally connected to the body to swing backward and forward but not sidewise and, when the device is arranged as a doll, as

shown in Fig. 1, the pivot connection for the legs is preferably a bolt 6 that extends through an aperture 60 in the body 1 and through the legs.

5 When the toy is of manikin shape, as shown in Fig. 2, the legs may be individually pivoted to their respective parts of the body by ordinary wood screws 62, as shown.

10 To provide for moving the legs 5—5 for alternately stepping forward or backward, as the toy is being pulled or pushed along and as presently more fully explained, a rocker device 7 is provided, which is in the nature of a flat block whose opposite ends 15 70—70 are tapered, see Figs. 3 and 5.

The device 7 is horizontally disposed on the bottom flattened end of the body on which it is rockably mounted by a stud screw or bolt 8 that passes through a central 20 aperture 71 in the rocker device and into the body 1, as shown.

25 By referring more particularly to Fig. 3 of the drawings, it may be noticed that the legs 5 at the inner side have horizontal sockets 50—50, the outer portions of which are flared as at 51 and the inner ends terminate in longitudinally elongated portions 52 and midway the said portions 52 and 51, the said sockets are just sufficiently wide to 30 permit of a close engagement therewith, at all times, of the tapered ends 70 of the rocker devices whose opposite ends extend into the sockets in the opposite legs 5—5, as shown.

35 By forming the leg sockets and the ends of the rocker devices and joining the said rocker device ends and the leg sockets in the manner stated and shown, as the said device 7 is rocked in the horizontal plane in 40 the manner presently explained, one leg will be forced forward as the other leg goes backward and the said shifting of the legs is effected without lost motion between the rocker ends and the legs, as will be readily 45 understood from the dot and dash positions of the legs, as indicated on Fig. 3.

To govern the length of the step and to provide for uniformity of action of the legs as they alternately swing in the stepping direction, stop portions 9—9 are 50 formed on the body 1 with which stop members 56—56 on the legs engage as the toy is being pulled along and the legs are swung backward in the manner presently explained.

The stops 9—9 may be arranged to suit the particular design of the toy. When of the doll shape, the stop shoulders 56 and the body stops 9, are arranged as in Fig. 4 55 but, when the toy is of the skeleton form as in Fig. 2, the stops 9—9 may be the ends of a cross piece 90 screwed crosswise onto the lower back end of the body 1, the stop portions 9—9 in the latter form being pro-

jected laterally of the body in position for being engaged by the legs, as they are rocked backward during the act of walking.

60 By joining the legs 5—5 with the body and connecting them with the rocker device 7, as stated, when the toy figure is placed in the upright position with the feet on the floor, by pulling or pushing the toy forwardly, the legs will assume a walking action and, as one leg advances, the forward step of the said advancing leg is limited by 70 the rocker device 7 imparting a corresponding backward swing of the other leg until the latter engages the stop 9 on its respective side of the body 1 and the now immovably held rocker device holds the advancing 75 leg from further forward stepping movement, it being understood that during the walking operation, the weight of the figure tends to tilt laterally in the direction of the lifted foot and thereby causes the foot 80 as it reaches the limit of its step to engage the floor and thereby relieve the other foot and leg of some of the weight of the said body to facilitate the forward or stepping movement thereof.

85 To provide for a gentle pulling or pushing of the toy, which is required for a perfect walking action, a pull lever 12 is used whose front end is tapered to form a wedge for entering and wedging into either of the 90 tapered sockets 13 and 14 in the front and back of the body 1.

To walk the toy apply the pull lever 12, for example as in Fig. 1, and the doll being 95 in the vertical position, pull the lever 12 slowly forward and, since there is always a slight difference in traction of the feet, the legs will assume a walking attitude, such operation or action being best explained as follows:

100 Assuming the left foot Fig. 1 as making the step forward in the direction indicated by the arrow x, the swing of the said leg oscillates the rocker device 7 and through the said device, the right leg is swung backwardly until its stop 56, see Fig. 4, engages the body stop 9 at that side.

105 The weight of the doll now shifts laterally onto the left leg which engages the floor, as the right leg is swung forwardly 110 to make it step, which motion is applied by reverse oscillation of the rocker member 7, the latter now swinging the left leg backward until its stop shoulder engages the body stop at that side, when the weight 115 of the body is again transferred onto the right leg and so on.

In pulling the doll forward, there should be no resistance to the lateral movement thereof, other than sufficient to keep the 120 doll from falling over.

125 The best result in the use of my toy is obtained by having the pull lever 12 con-

nect with the body 1 in line with the leg joints and to provide the said pull member with a handle that flexibly joins with the outer edge thereof in the manner best 5 shown in Figs. 6, 7 and 8, from which it will be noticed that the said handle 15 has a vertically elongated socket 16 that tapers outwardly and the said handle is joined with the inner end of the lever 12 by a cross 10 pin 17 that passes through an elongated aperture 18 in the pull lever.

The idea of connecting the handle 15 to the pull member 12, as shown, is, a child 15 who naturally grasps the handle very stiffly but not having hold of the member 12, the necessary rocking movement of the member 12 is provided for through the flexible connection of the handle and the member 12.

20 The socket is vertically extended and is made oblong because, if it were not, the child would not hold the handle perfectly level and the top and bottom of the socket opening would strike against the member 12 and 25 interfere with the walking of the doll.

The member 12 must swing freely in the vertical plane in the handle 15 and be held in contact at the sides with the said handle to keep the doll from falling over.

30 In my construction of doll, the foot that is up is always moving forward by reason of pulling on the handle 12 and the rocker device which causes the feet, when moving, to always move past each other, backward 35 or forward.

What I claim is:

1. A walking toy that includes a body, a pair of stiff legs pivotally connected to the body to swing backwardly and forwardly 40 relatively to the said body, a pull member connectible with the body and adapted to project in the walking direction of the toy, and means coöperating with the body and the legs for imparting a reverse movement to one leg as the other leg moves forward, as the body is pulled forwardly or backwardly.

2. A walking toy that includes a body, a pair of stiff legs pivotally connected to the 50 body to swing backwardly and forwardly relatively to the said body, means connectible with the body and adapted to project in the walking direction of the toy, and means coöperating with the body and the legs for imparting a reverse movement to one leg as the other leg moves forward, as the body is pulled forwardly or backwardly, the first 55 stated means comprising a lever having its free end shaped to connect with the body of the toy and a handle flexibly connected to the outer end of the lever.

3. A walking toy that includes a body, a pair of stiff legs pivotally connected to the body to swing backwardly and forwardly

65 relatively to the said body, means connectible with the body and adapted to project in the walking direction of the toy, and means coöperating with the body and the legs for imparting a reverse movement to one leg as the other leg moves forward, as the body 70 is pulled forwardly or backwardly, the first stated means comprising a lever having its free end shaped to connect with the body of the toy and a handle flexibly connected to the outer end of the lever, the said handle 75 including a vertical elongated socket into which the outer end of the pull member extends, and a connection that joins the pull member and the handle and which permits of relatively vertical movement of the 80 handle and the pull member and holds the said pull member from lateral motion.

4. A walking toy comprising a body, a pair of rigid legs having hip joint connections with the body for permitting forward 85 and backward swinging thereof, a rocking device pivotally mounted on the body and having its opposite ends held in flexible engagement with the legs, whereby, as the body and the legs are pulled along, 90 as one leg moves forwardly, the oscillation of the said device operates to swing the other leg backwardly.

5. A walking toy comprising a body, a pair of rigid legs having hip joint connections with the body for permitting forward 95 and backward swinging thereof, a rocking device pivotally mounted on the body and having its opposite ends held in flexible engagement with the legs, whereby, as the 100 body and the legs are pulled along, as one leg moves forwardly, the oscillation of the said device operates to swing the other leg backwardly, and stop devices on the body engageable by the legs on their backward 105 swing to limit the backward and forward swing of such legs.

6. A walking figure toy that includes a body, legs having hip joint connections with the body, whereby to move forwardly and 110 backwardly but not sidewise with respect to the said body, means for pulling the toy with its foot portions along a base, other means coöperating with the body and the legs adapted for moving one leg backward 115 as the other leg is swung forward, when the toy is pulled along.

7. A walking figure toy that includes a body, legs having hip joint connections with the body, whereby to move forwardly and 120 backwardly but not sidewise with respect to the said body, means for pulling the toy with its foot portions along a base, and other means coöperating with the body and the legs adapted for moving one leg backward 125 as the other leg is swung forward, when the toy is pulled along.

8. A walking figure toy that includes a

body, legs having hip joint connections with the body, whereby to move forwardly and backwardly but not sidewise with respect to the said body, means for pulling the toy 5 with its foot portions along a base, other means coöperating with the body and the legs adapted for moving one leg backward, as the other leg is swung forward, when the toy is pulled along, the said pulling means

including a member having one end shaped 10 for connecting with the toy body, and a handle connected to the other end of the said pull member, the latter and the handle having a relatively vertical oscillation, whereby to avoid a rigid gripping of the 15 member that pulls the toy along.

FRANK CRIEST.
